UNITED STATES PATENT OFFICE

2,451,250

ELAPSED TIME INDICATOR

Hans Springer, Ashland, Mass., assignor to Telechron, Inc., a corporation of Maine

Application November 22, 1946, Serial No. 711,682

5 Claims. (Cl. 161—23)

1

My invention relates to elapsed time indicators such as will be useful in timing predetermined adjustable time intervals such, for example, as cooking or photographic developing operations and the like.

Its object is to provide a simple, rugged, inexpensive timer of this type which is adjustable as to the timed interval, including both initial time settings and plus or minus changes thereof during the time interval, which gives an accurate indication of the time setting and the time remaining in the time interval at all times during such interval, and which produces an alarm at the end of the time interval. A further object of the invention is to provide an interval timer of the character described in which all of the operations incident to setting, timing, alarm operation and alarm shutoff are performed by turning a single shaft in opposite directions either by a timer motor or manually.

The features of my invention which are believed to be novel and patentable will be pointed out in the claims appended hereto. For a better understanding of my invention, reference is made in the following description to the accompanying drawing in which Fig. 1 represents a face view of my elapsed timer and Fig. 2 a side sectional view thereof taken on line 2-2 of Fig. 1. Fig. 3 is a front view but with the glass cover, holding rim, and most of the front stationary indicator dial removed. Fig. 4 is a view taken on line 4-4, Fig. 1, of an upper portion of the structure to help in showing the disposition of a part 40 used for guiding a movable indicator 34 through a slot 36 in a front dial 13. Figs. 5, 6, and 7 are front views with the greater portion of the front indicator parts broken away to show the driving mechanism and an operating cam in different positions. Fig. 5 represents a full alarm off position; Fig. 6 a time interval setting position, and Fig. 7 an alarm on position.

Referring first primarily to Fig. 1, the device includes a self-starting synchronous clock motor having a two-pole magnetic field structure 1 with an energizing coil 2 on its yoke and an armature, not shown, but contained within a reduced diameter portion 3 of a casing 4 containing speed reducing gearing between the motor armature and a terminal drive shaft having thereon a gear pinion 5. The pole pieces of the field structure embrace the portion 3 of the casing and are separated from the rotor only by the thin shell of the non-magnetic casing. A motor structure of this character is shown in detail in United States Patent No. 1,495,936. The motor is riveted or otherwise

2

secured to the rear of a plate 6. One end of a resilient magnetic vibrating armature member 7 is secured to plate 6 at 8 (see Figs. 4 and 5) and extends generally parallel with the yoke of motor field core 1 outside the coil 2 with its ends sufficiently close to the core structure that it shunts a limited portion of the flux of the motor field core between the ends of coil 2. The coil 2 is energized by single-phase alternating current so that the resulting pulsating flux causes the armature member 7 to vibrate in synchronism with the flux pulsations when such armature is free to do so. Its right-hand free end, as best shown in Figs. 2, 4, and 6, may then strike against a magnetic bushing 9 secured to the field core 2 to produce an audible alarm. The armature member 7 may, however, be held against vibration and thus remain silent by reason of an extension 10 thereof resting against the high parts of a cam 11 as shown in Figs. 5 and 6 and as will be explained more in detail later.

Spaced to the front of and secured to plate 6 is another plate 12 which forms the rear housing portion of the elapsed timer dial structure which 25 includes a stationary indicator dial 13, a glass front cover 14 and an outer bezel ring 15 which secures the glass cover and dial plate 13 to housing plate 12. The dial 13 is spaced to the front of housing plate 12 by reason of spacing lugs 16 pressed out to the front from plate 12. Likewise 30 the glass cover 14 is spaced slightly to the front of stationary dial plate 13 by reason of a spacing ring 17 preferably made of a slightly compressible gasket material. Lugs 18 extending forward from plate 12 embrace dial plate 13 at two or more points about its periphery to help position and hold it in place, and lugs 19 extending to the rear from the outer bezel ring are bent around to the rear of spacing lugs 16 of plate 12 to secure the bezel ring 15 in place, thereby holding the glass cover against gasket 17 and the gasket against dial plate 13.

The space between plates 6 and 12 is occupied by reduction gearing between the terminal pinion 5 of the motor-unit and a shaft 20 having bearings 45 in plates 6 and 12 and extending forward through openings at the centers of dial plate 13 and glass cover 14 and having an operating thumb-piece 21 secured on its front end and accessible at the front of the timer. The gear reduction just referred to includes the gears 22, 23, 24, 25 and a mutilated gear 26 on shaft 20 best shown in Fig. 5. This gear train also includes a slip friction clutch indicated at 27, Fig. 5, between gears 24 and 25. Secured on the rear of shaft 20 is the cam 11

which cooperates with the alarm armature as previously mentioned. The cam 11 with its cam follower 10 not only has the usual cam actions but also acts as a two-way stop to limit the travel of the cam in opposite directions. This is by reason of the short radial projection 28 on the cam periphery. The greater length of the cam periphery is occupied by the raised surface 29 on which the cam follower 10 rides to hold the alarm armature 7 raised and prevents the same from vibration during a timing interval. The relatively short depression 30 in the cam when opposite the cam follower 10 as represented in Fig. 7 allows the armature 7 to vibrate freely and the alarm to sound at the end of a timing interval. The notch 31 in the cam surface is for the purpose of receiving the cam follower at the termination of a timing interval after the alarm has been silenced manually, as shown in Fig. 5. In this position the cam follower vibrator 7 is raised sufficiently to prevent alarm operation, and the notch 31 prevents easy accidental turning of the cam clockwise from this position, while the stop prevents counterclockwise rotation of the cam beyond this position.

Also secured to shaft 20 is an indicator member having a hub part 32, a radial spider part 33, and a C-shaped sector part 34, which extends around to the right from the radial spider part 33 nearly 360 degrees in the arc of a circle concentric with shaft 20. The purpose of this indicator is to indicate at all times the time setting of the elapsed time indicator on the graduated time dial 35 about the periphery of dial plate 13, and if the device is a considerable distance from the observer so that the graduations cannot be read, to indicate at all times the approximate time setting of the device. These indications are present at the time the device is initially set and at all times during the remainder of the timing interval to show the time remaining in the interval. The indicator sector 34 and its spider 33 are of relatively thin, somewhat flexible, material to permit the greater portion of the sector 34 to pass through a radial slit 36 in the dial plate 13 so that the greater portion of sector 34 may lie in front or all completely behind the dial plate depending on the rotary position of the indicator 34. That portion which is in front of the dial plate lies loosely in a track or depression 37 in the front of dial plate 13. This depression begins at the slit 36 and extends around the dial plate in a clockwise direction about 310 degrees to the point 38 opposite the upper end of the time graduated scale 35. The depression gradually becomes shallower from the slit 36 to point 38, is concentric with shaft 20, and is of a radial width slightly greater than the radial width of indicator sector 34 so as to accommodate that portion of sector 34 which is exposed in front of the dial plate with the front surface of the sector approximately flush with the raised or time graduated portion of the dial plate. Also the front surface of the indicator member or at least the sector 34 part thereof has a color which contrasts with the front surface of the dial plate. Thus the dial plate may be polished brass with black time graduations, and the front surface of the indicator may be enameled in red.

To assure that the free end 39 of the colored indicator sector 34 will always pass through slit 36 when the sector is turned clockwise from the completely unexposed position to a partially exposed position, a guide member 40 is preferably provided. This guide member is secured to the front side of plate 12 and has a short sector spaced

from plate 12 on the same radius as sector 34 and which extends in a clockwise direction a short distance through the slit 36 as best shown in Figs. 1, 2, 3, and 4. It is to be noted that the slit 36 is cut in dial plate 12 at the counterclockwise end of the depressed sector portion 37 thereof or between a raised and depressed portion of plate 12 so that the slit in effect faces in a clockwise direction from behind to the front of dial plate 12. The guide 40 rests tight against the depressed surface portion of this slit and has the effect of continuing the depressed track portion 37 through the slit in a counterclockwise direction. When the colored indicator sector 34 is rotated clockwise from the fully concealed position, such as represented in Fig. 3, the free end 39 thereof is guided through the slot 36 by the guide 40. The spider end of sector 34 moves behind the guide 40 when the sector is rotated counterclockwise to its extreme counterclockwise position and that portion of guide 40 which extends through slit 36 hides any portion of the colored sector 34 behind the guide which might otherwise be seen through the slit (see Fig. 4). There is a slight spiral shape to the sector 34 so that its free end 39 is displaced slightly toward the front of the device as compared to the spider end thereof. This spiral shape conforms generally to the corresponding change in depth of the depressed track 37 in the dial plate. The design is such that the shaft 20 with the cam 11 and indicator 34 thereon may be easily rotated by the timer motor 1 through the gear train and friction clutch 21, or manually by the thumb-piece 21 with clutch 27 slipping when gears 25 and 26 are in mesh. The construction is such as to provide a compact, closely spaced, and relatively thin dial assembly such as is shown in Fig. 2.

The relative rotary positions of the cam 11, the mutilated gear 26, and the indicator sector 34 on shaft 20, and the relative rotary positions of these parts with respect to the parts with which they cooperate are such as to insure their proper sequence of operation in accomplishing the results desired.

In Fig. 5 the cam follower 10 is shown in the notch 31 and against stop projection 28 of cam 11. This is the full or manually off position of the device. The vibrator arm 7 is lifted and does not vibrate. The mutilated portion of gear 26 is opposite gear 25 and there is no driving connection between the timer motor and cam shaft 20. The colored indicator sector 34 is completely hidden behind the time indicating dial with its free end 39 in an upper center position as represented in Fig. 5. Thus in this position the alarm is turned off, the timer indicator is disconnected from the motor and the time indication is zero. This is the normal condition of the apparatus when not in use. The motor may be energized or not as desired.

To make use of the device to time an interval, the motor is energized, if deenergized. The thumb-piece 21 is turned clockwise, rotating the parts attached thereto accordingly. Cam follower 10 rides out of notch 31 into the depression 30. This may cause the alarm to sound momentarily if the manual setting operation is slow and corresponds to the position of the parts shown in Fig. 7. However, it is assumed that in such a setting operation the manual clockwise rotation will be sufficiently rapid that the sounding of the alarm will hardly be noticeable, if it is noticeable at all. The cam follower is then pushed up as it rides out of the depression 30 onto the raised

part 29 of uniform radius of cam 11. Just at the point where the cam follower 10 is raised out of depression 30 in rotating the parts clockwise, the free end of indicator sector 34 appears through slot 36, and the counterclockwise end of the toothed portion of mutilated gear 26 meshes with its driving gear 25. This manual clockwise setting operation is continued until the free end 29 of colored sector 34 is opposite the time graduation desired, say for example 40 on the graduated scale 35. In such portion of the setting operation the gear 25 is driven manually by gear 26 in the opposite direction to that which it is driven by the timing motor, and the clutch at 27 slips.

The device is now set for a timing interval of 40 which may be seconds or minutes or any other time units, depending on the gear reduction ratio used. The gearing represented assumes that the terminal pinion 5 of the motor operates at 3.6 revolutions per minute and that the time dial of the device is graduated in minutes. The thumb-piece 21 is now released and the timer motor drives the colored sector 34 counterclockwise at a rate such that it will disappear through slot 36 in exactly 40 minutes. It is to be noted that if at any time during the 40-minute time interval it is desired to reset the device for a shorter or longer timing interval, it can be done. Also, that the free end of the colored sector 34 at all times indicates on the graduated scale the time remaining in the time interval and that the exposed length of the sector is likewise a measure of the time remaining in the time interval and can be seen from a considerable distance.

At the end of the 40 minute interval cam follower 10 drops into depression 30, sounding the alarm, and simultaneously the clockwise end of the gear sector of gear 26 is disengaged with gear 25. The device will stay in this condition until reset or turned full off by hand. The alarm can be silenced by turning thumb-piece 21 counterclockwise to raise cam follower 10 into notch 31. The stop projection 28 in cooperation with the cam follower prevents the manual turning of the shaft 20 too far in either direction and can have a peripheral length as long as desired for this purpose. Figs. 1 and 2 indicate the colored sector 34 to be in approximately the full off position. Fig. 6 represents approximately a 54-minute time setting with the free end 29 of colored sector 34 exposed opposite the 54-minute graduation. On the front of the time dial just to the inside of the indicator track 37 there are preferably arrows with the notations "On" and "Off" to indicate the directions in which the knob 21 should be turned for turning the timer on as in a time setting operation and for turning the timer off to silence the alarm at the end of a timing operation. It is noted that the teeth of gear 26 are omitted over that section which is opposite driving gear 25 when the cam 11 is between the positions shown in Figs. 5 and 7 where only manual operation of the timer shaft 20 is desired.

If desired, a remote electrically actuated alarm may be sounded at the end of a time interval and a normally open switch 40, Fig. 7, is represented for this purpose arranged to be closed by a pin 41 in cam 11 in the alarm sounding position only. The switch 40 may also be used to open or close an electrical circuit for a heating unit in a cooking appliance or other device.

The same pin 41 may be used to open the circuit of the timer motor by means of a normally closed switch 42 which is arranged to be opened by pin 41 only in the full manually off position. By such

an arrangement the motor is shut off by knob 21 with the shutting off of the alarm and is turned on again when the timer is set for a timing operation. This assures that the motor will be energized only during timing and alarm sounding operations, without the necessity of any attention by the user of the device except that incident to the manual turning of knob 21 for the other purposes described.

10 What I claim as new and desire to secure by Letters Patent of the United States is:

1. An elapsed time indicator comprising a timer motor, a rotary shaft, a driving connection between said motor and shaft including a slip friction clutch and a mutilated gear through which said shaft may be driven in one direction an amount limited to less than one complete revolution by reason of the mutilated gear, manual means for turning said shaft in either direction, such manual turning being permitted when the shaft is in driving relation with the timer motor by reason of the slipping of said clutch, an alarm, a cam on said shaft, a cam follower bearing against said cam for controlling the operation of said alarm, an indicator on said shaft, a graduated time dial on which said indicator indicates to show the rotary position of said shaft, the cam surface of said cam having a long raised surface, a short depressed surface, and a short raised surface extending about the cam in the order named in the direction opposite to that in which the cam is adapted to be driven by the timer motor, and a stop projection on the cam between the long and short raised surfaces which prevents movement of such stop projection past the cam follower in either direction, said timer motor being in driving connection with said rotary shaft only when the cam follower is resting on the long raised portion of said cam, said indicator indicating at the zero end of said scale when the cam follower is in the short depressed portion of said cam and at the other end of the graduated scale when the cam follower is on the long raised portion of said cam and adjacent the stop projection and said cam follower permitting the alarm to sound only when in the short depressed portion of said cam.

2. An internal timer comprising a timer motor, an alarm, a cam follower for controlling said alarm, a graduated time dial, a rotary shaft, a driving connection between said timer motor and shaft including a mutilated gear on said shaft and a slip friction clutch, a cam on said shaft for controlling the operation of the alarm through the cam follower, an indicator on said shaft cooperating with said time dial to indicate the time setting of said timer, a manual thumb-piece for rotating said shaft for the purpose of setting the timer and shutting off the alarm, and stop means for limiting the rotation of said shaft to slightly less than a complete revolution, the arrangement and relative rotary relation of the parts secured to the rotary shaft being such that the timer motor may drive the shaft only in one direction from a stopped position where the indicator gives a maximum time indication on said scale to an alarm sounding position where the indicator indicates zero on said scale whereat the motor is disconnected from driving relation with said shaft by reason of the mutilated gear and the cam allows the cam follower to move to the alarm sounding position to sound the alarm only in such rotary position, said shaft having a further limited range of rotary movement between the alarm sounding position and the other stop-

ped position during which it is disconnected from the timer motor and over which it may be moved manually from alarm sounding position to shut off the alarm.

3. An elapsed time indicator comprising a stationary dial having a circular time graduated scale thereon extending over a substantial portion of a circle and having a radial slit therein in radial alignment with the zero time graduation of such scale, an indicator rotatively mounted behind the dial on an axis concentric with the circular time scale, said indicator having a radial spider portion and a sector-shaped indicator portion of a color contrasting with said dial, the sector portion being secured to the spider portion at one end only and with its free end extending in an upscale direction concentric with the axis of rotation on a radius to permit it to pass through said radial slit when the indicator is rotated, said indicator having a range of rotation from a position where it is completely hidden behind the dial to a position where it is largely exposed with its free end in radial alignment with the upper end of said time scale, means for guiding said sector through the slit when rotated, a timer motor, a drive connection between said motor and indicator including a slip friction clutch and a mutilated gear by means of which said motor may drive said sector in a downscale direction only between maximum and zero time indication at a rate corresponding to the time graduations, manual means for rotating said sector in either direction over the same range and over an additional range of movement where the sector is hidden behind the dial, and an alarm actuated in response to the arrival of said indicator at a zero time indicating position and cut off by movement of said indicator in either direction from said last-mentioned position.

4. An elapsed time indicator comprising a stationary dial having a circular time graduated scale thereon extending over a substantial portion of a circle and having a radial slit therein in radial alignment with the zero time graduation of such scale, an indicator rotatively mounted behind the dial on an axis concentric with the circular time scale, said indicator having a radial spider portion and a sector-shaped indicator portion of a color contrasting with said dial, the sector portion being secured to the spider portion at one end only and with its free end extending in an upscale direction concentric with the axis of rotation on a radius to permit it to pass through said radial slit when the indicator is rotated, said indicator having a range of rotation from a position where it is completely hidden behind the dial to a position where it is largely exposed with its free end in radial alignment with the upper end of said time scale, means for guiding said sector through the slit when rotated, an alternating current timer motor, a driving connection between said motor and indicator including a slip friction clutch and a mutilated gear whereby the indicator may be driven in a downscale direction at a rate corresponding to said time graduated scale only over the exposed range of movement

of the indicator, manual means for rotating said indicator in either direction over its exposed range and over an additional completely hidden range, an alarm device energized by said motor, a cam follower for controlling the operation of said alarm, and a cam rotated with said indicator for actuating said cam follower to permit the operation of said alarm only when the indicator is in approximately a zero time indicating position.

5. An elapsed time indicator comprising a stationary dial having a circular time graduated scale thereon extending over a substantial portion of a circle, and having a radial slit therein in radial alignment with the zero time graduation of such scale, an indicator rotatively mounted behind the dial on an axis concentric with the circular time scale, said indicator having a radial spider portion and a sector-shaped indicator portion of a color contrasting with said dial, the sector portion being secured to the spider portion at one end only and with its free end extending in an upscale direction concentric with the axis of rotation on a radius to permit it to pass through said radial slit when the indicator is rotated, said indicator having a range of rotation from a position where it is completely hidden behind the dial to a position where its free end is in radial alignment with the upper end of said time scale, means for guiding said sector through the slit when rotated, an alternating current timer motor, a driving connection between said motor and indicator including a slip friction clutch and a mutilated gear whereby the indicator may be driven in a downscale direction at a rate corresponding to said time graduated scale only over the exposed range of movement of the indicator, manual means for rotating said indicator in either direction over its exposed range and over an additional completely hidden range, an alarm device energized by said motor, a cam follower for controlling the operation of said alarm, a cam rotated with said indicator for actuating said cam follower to permit the operation of said alarm only when the indicator is in approximately a zero time indicating position, and means operated in response to the manual rotation of said indicator in a downscale direction beyond its zero time indicating position for deenergizing said timer motor.
